(57) **CLAIM**

The ornamental design of a cable hanger, as shown and described.

DESCRIPTION

FIG. 1 is a front elevation view of a cable hanger according to the present invention;

FIG. 2 is a rear elevation view thereof;

FIG. 3 is a right side elevation view thereof;

FIG. 4 is a left side elevation view thereof;

FIG. 5 is a second front elevation view thereof;

FIG. 6 is a second rear elevation view thereof;

FIG. 7 is a second right side elevation view thereof;

FIG. 8 is a second left side elevation view thereof;

FIG. 9 is a top view thereof; and,

FIG. 10 is a bottom view thereof.

The broken lines shown in the figures described above are for illustrative purposes only and form no part of the claimed design. The special broken line crossing the end diameter of the claimed cable hanger shaft in FIGS. 5 through 8 defines the bounds of the claimed design and forms no part of the claimed design. It is noted that any difference in shading indicates a contrast of appearance and does not depict any particular color, texture, or material.
